UNITED STATES PATENT OFFICE.

JOSEPH T. BEDFORD, OF NEW YORK, N. Y.

MACHINE FOR COATING PAPER WITH WAX, &c.

SPECIFICATION forming part of Letters Patent No. 243,353, dated June 28, 1881.

Application filed November 9, 1880. (No model.)

To all whom it may concern:

Be it known that I, JOSEPH T. BEDFORD, a citizen of the United States, residing at New York, in the county and State of New York, have invented a new and useful Machine for Coating Paper with Wax or other Material, of which the following is a specification.

My invention relates to improvements in paper-coating machines in which a melting-tank for wax, glue, paraffine, or other suitable material is used in conjunction with an adjustable elevator or deliverer of said material, and a heated roller, a cooling-fan, and a feeding apparatus.

The objects of my invention are to provide the paper with a uniform coat of any desired thickness of coating material in a very simple manner, and deliver it in an even condition, without wrinkles or ruffles. I attain these objects by the mechanism illustrated in the accompanying drawings, in which—

Figure 1 is a top view of my paper-coating machine. Fig. 2 is a vertical central longitudinal section of the same. Fig. 3 is a detail view of an adjusting-clamp used in the delivering or coating device. Fig. 4 is a detail view of an adjustable roller-bearing used in the coating device. Fig. 5 is a detail view of the roller-bearings used in the feeding device.

Similar letters refer to similar parts throughout the several views.

A is a suitable frame, B a paper-roll, C a coating device, D a cooling device, and E the feeding device, of my machine.

The paper-roll B is supported by a central shaft, *b b*, the ends of which rest upon anti-friction rollers *f f*, suitably attached to the frame A, whereby the discharge of the paper sheet *b'* from the roll B is effected without strain to the paper, no matter how large and heavy the roll may be. From the roll B the paper sheet *b'* passes over a guide-roller, *G*, thence under a heated roller, *H*, of the coating device C, and thence over another guide-roller, *G'*. The two guide-rollers *G G'* are in part elevated above the bottom surface of the roller *H*, as shown, and thus cause the paper sheet *b'* to pass partly around said roller, and become thoroughly and uniformly heated by the same, and consequently well prepared to receive its coating. To prevent the

paper sheet *b'* from lifting the roller *H* out of its desired level the journals *h* of said roller are hung in slotted bearings *h'* of suitable stands, *H'*, which are provided with vertical set-screws *h²*, and movable top bearings, *h³*, whereby the roller can be adjusted to any suitable elevation. While the paper sheet *b'* is being heated it is also pressed down by the roller *H* upon a felt block, *I*. This felt block *I* is held suspended by means of a clamp consisting of two jaws, *J*, and set-screws *j*, as in Fig. 3. The upper portion of the felt *I* passes between the jaws *J*, and by screwing said jaws more or less together upon the felt the felt becomes more or less compressed, and its capillary attraction more or less restricted or diminished, and thus I control the amount of coating material in its ascent through the felt, and its delivery upon the paper sheet *b'*. The clamp *J J* rests upon the lid *k* of a tank, *K*, of the coating device, and holds the felt in contact with the paper above, while at the same time it keeps the felt partially immersed in the coating material in the tank. The roller *H* and tank *K* are heated by suitable ordinary heating devices. From the roller *G'* the paper sheet *b'* passes (as indicated by arrows) around three guide-rollers, *L L' L²*, which are arranged in relative triangular position, as shown, and over or around which the paper sheet passes, so as to form an open angle or free space at the bottom. Beneath the apex of this triangular arrangement of the rollers *L L' L²* a fan, *M*, is suitably hung to the frame *A*, which fan is revolved by the main shaft *N* of the machine by means of wheels *m n*, and thus rapidly cools and dries the paper sheet. The paper so treated passes over another guide-roller, *L³*, to the feed-rollers *O O'* of the feeding device *E*, the lower one of which, *O*, is hung in rigid bearings of suitable bearing-stands, *P*, and the upper one, *O'*, rests upon the lower roller, and is kept in place by means of vertical guide-slots *p*.

By means of set-screws *p'*, bearing upon the upper bearing-blocks, *p²*, in the slot, the roller *O'* can be forced down upon the roller *O* to any desired extent, so that the paper sheet *b'* is not only safely and uniformly drawn through the machine, but may also be delivered with a calendered surface.

The several guide-rollers described, and the

roller O, are provided with pulleys $g' l l' p' p$ ^o, respectively, which are driven by belts from pulleys $n' n^2$ upon the main shaft N, and m' on the fan-shaft, as shown, at a uniform speed.

5 The guide rollers and shafts are all provided with suitable bearings of known construction, and these are all fastened to the frame A of the machine.

The coating material principally used will 10 be paraffine; but wax, oil, glue, or any other material which can be melted or kept in a dissolved state may be used in my machine for coating paper.

Prior to my invention porous materials for 15 conducting moist substances to paper and other like materials were used, and in some instances such materials had been confined adjustably by clamps; but such porous materials were not employed for the purpose and in combination 20 with other parts as set forth in my specification.

I claim—

1. The combination, with rollers for pressing and smoothing the paper or other material 25 being coated with wax or like substance, of a trough containing coating substance, and a sheet or block of felt, or of similar absorbent and conducting material, suspended in the trough and beneath the roller H, and bearing 30 with its upper edge against the surface of the paper being coated, substantially as and for the purpose described.

2. The combination, with rollers for pressing and smoothing the paper or other material being coated with wax or like substance, 35 of a trough containing coating substance, and a sheet or block of felt or similar absorbent and conducting material, and clamps which are made adjustable with respect to the sheet of felt, for the purpose of rendering it more 40 or less porous, substantially as and for the purpose set forth.

3. The combination of the heating and pressure roller H, rollers G G', and coat-elevating felt I, substantially as and for the purpose set 45 forth.

4. The combination of a coating device consisting of a trough, pressure-roller H, rollers G G', and a sheet of felt, a feeding device consisting of rollers O O' and pressure-screws p' , 50 and a cooling device consisting of a fan and rollers, L L' L², substantially as and for the purpose described.

5. The combination of the deflecting guide-rollers L L' L² and fan M, intermediate of the 55 rollers L L², substantially as and for the purpose set forth.

Signed in presence of two subscribing witnesses.

JOSEPH T. BEDFORD.
